UNITED STATES PATENT OFFICE.

SAMUEL M. VAUCLAIN, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA. LOCOMOTIVE.

1,171,283.

Specification of Letters Patent.

Patented Feb. 8, 1916.

Application filed November 18, 1914. Serial No. 872,841.

To all whom it may concern:

Be it known that I, SAMUEL M. VAUCLAIN, a citizen of the United States, residing in Philadelphia, Pennsylvania, have invented certain Improvements in Locomotives, of which the following is a specification.

My invention relates to certain improvements in compound locomotives of the "centipede" type, *i. e.*, the type in which there are three pairs of cylinders. In this instance there are three independent frames connected by articulated joints, and two cylinders are mounted on each frame, one at each side of the locomotive. There are eight driving wheels for each set, but it will be understood that the construction may be modified without departing from the essential features of the invention.

One object of the invention is to couple the cylinders so that one high pressure cylinder will exhaust into two low pressure cylinders at one end of the locomotive and the other high pressure cylinder will exhaust into the two low pressure cylinders at the opposite end of the locomotive.

Another object of the invention is to make all of the cylinders of the same size, thus materially economizing in the cost of the manufacture of a locomotive.

A still further object of the invention is to arrange the cylinders so that the pipes leading from the boiler to the high pressure cylinder will be fixed in relation to the cylinder and boiler while the jointed pipes will carry the low pressure steam leading from the high pressure cylinder to the low pressure cylinders.

These objects, and other advantageous ends, I secure as hereinafter set forth reference being had to the accompanying drawings, in which:

Figure 1 is a side view in diagram, illustrating my invention as applied to a "centipede" type of locomotive; and Fig. 2 is a plan view of the cylinders and their connecting pipes.

Referring to the drawings, 1 is the boiler

of a locomotive, having a fire box 2 at one end and a smoke box 3 at the opposite end. 54 4 is the cab of the locomotive in the present instance.

5 is the tender.

6 is the intermediate frame. 7 is the forward frame and 8 is the rear frame. These 68 frames are connected together by articulated joints, as fully set forth in the patent granted to George R. Henderson, No. 1,013,771, dated January 2, 1912.

The boiler is rigidly secured to the central 68 frame 6 and swings over the front frame 7. The rear frame carries the tender 5. Mounted on the intermediate frame are the high pressure cylinders 9 and 10, one located on one side of the locomotive and the other located on the opposite side, as clearly illustrated in Fig. 2. Each of these cylinders is provided with a steam chest 11 of any of the ordinary types. On the forward frame 7 are mounted the low pressure cylinders 12 and on the rear frame 8 are mounted the low pressure cylinders 13.

14 is a pipe leading from the steam dome of the boiler 1 through the smoke box and is connected to pipes, one on each side of the 75 locomotive, as shown in Fig. 2. The pipe 14 may be connected, as shown, to a superheater 16 having pipes which extend into the tubes of the boiler. The pipes 15 are rigidly connected both with the boiler and with the steam chest of the cylinders 9 and 10, as the frame 6 on which the cylinders are mounted is rigidly secured to the boiler so that there is no need of any split joints, or other loose connections.

The cylinder 10 exhausts into a pipe 17 leading to the steam chest of the low pressure cylinders 12 at the forward end of the locomotive. As steam from the cylinder 10 exhausts into both cylinders 12 it acts expansively in said cylinder. The pipe 17 is flexibly connected at 18 to the cylinder structure 19 of the high pressure cylinders 9 and 10 and there is a flexible joint 20 in said pipe near the low pressure cylinders 12 98 as the frame 7, on which the cylinder 12 is

mounted, is pivotally connected to the frame 6 on which the cylinders 9 and 10 are mounted. Low pressure steam passes through this pipe and it can be packed against leakage, 5 which is practically impossible when a telescopic and jointed pipe is used for the passage of the high pressure steam. The high pressure cylinder 9, in the present instance, exhausts into a pipe 21 leading to the steam chest of the low pressure cylinders 13 and the pipe is flexibly connected at 22 with the structure 13 of the low pressure cylinders and has a telescopic joint 23. The low pressure cylinders 12 exhaust through a pipe 24 10 and through the nozzle 25 into the smoke box of the boiler 1, acting to create a draft through the stack and the boiler. The cylinders 13 exhaust through a pipe 26 which is connected to the exhaust pipe 27 at the 15 rear of the tender. Intermediate of the pipes 26 and 27 is the feed water heater 28, located under the tender. This feed water heater is connected with the water compartment of the tender and with the water supply of the boiler.

By the above construction, it will be understood that high pressure steam passes from the boiler directly to the high pressure cylinders which are rigidly connected to the 30 cylinders carried by the frame on which the boiler is also rigidly mounted and both sets of low pressure cylinders, which are pivoted to the central frame, are connected respectively to the two high pressure cylinders 35 through the flexible pipes and as these flexible pipes convey the low pressure steam there is not the same danger of leakage as there would be if they conveyed the high pressure steam.

40 While I have illustrated the exhaust from the rear cylinders as passing through the feed water heater, and the main steam pipe 14 as connected with the superheater 16, these elements may be omitted without departing from the essential features of the 45 invention.

I claim:

1. The combination in a locomotive, of 50 three pairs of cylinders spaced apart; a boiler; high pressure pipes leading from the boiler to a central pair of cylinders; a low pressure pipe leading from one of the high pressure cylinders to the two low pressure cylinders at one end; and a second pipe 55 leading from the other high pressure cylinder to the low pressure cylinders at the opposite end.

2. The combination in a locomotive, of 60 three frames pivotally connected; driving mechanism on each frame; two cylinders on each frame; a boiler rigidly mounted on the central frame and overhanging the forward frame; two pipes leading from the live steam supply of the boiler to the cylinders

on the intermediate frame; a flexibly connected pipe leading from one of said cylinders on the intermediate frame to the cylinders on the forward frame; and a flexibly connected pipe leading from the other cylinder on the intermediate frame to the two 70 cylinders on the rear frame.

3. The combination in a locomotive, of three frames connected together by articulated joints; independent driving mechanism mounted on each frame; two cylinders 75 mounted on each frame, all of the cylinders being of the same diameter; a boiler mounted on the intermediate frame and overhanging one of the other frames; two high pressure pipes leading from the steam supply of 80 the boiler to the cylinders on the intermediate frame; a pipe leading from one of the intermediate cylinders to the two cylinders at the forward end of the locomotive; and a pipe leading from the other cylinder on the 85 intermediate frame to the cylinders mounted on the rear frame.

4. The combination in a locomotive, of three frames connected together by articulated joints; independent driving mechanism 90 mounted on each frame; two cylinders mounted on each frame; all of the cylinders being of the same diameter; a boiler mounted on the intermediate frame and overhanging one of the other frames; two high pressure 95 pipes leading from the steam supply of the boiler to the cylinders on the intermediate frame; a pipe leading from one of the intermediate cylinders to the two cylinders at the forward end of the locomotive; a pipe 100 leading from the other cylinder on the intermediate frame to the cylinders mounted on the rear frame; the forward cylinders exhausting into the smoke box of the boiler; and a feed water heater through which the 105 exhaust passes from the rear cylinders.

5. The combination in a locomotive, of three frames connected together by articulated joints; driving wheels mounted on each frame; two cylinders mounted on each 110 frame and connected to the driving wheels so that the mechanism on each frame is independently driven; a boiler mounted on the intermediate frame and overhanging the forward frame; a tender mounted on the 115 rear frame; a pipe leading from the steam dome of the boiler; two high pressure pipes leading from said pipe to the steam chest of the cylinders on the intermediate frame; a flexibly connected pipe leading from the exhaust side of one of said cylinders to the steam chest of the forward cylinders; a flexibly connected pipe leading from the cylinder on the intermediate frame to the steam chest of the low pressure cylinders on the rear 120 frame; a pipe leading from the exhaust side of both forward low pressure cylinders to the smoke box of the boiler, said pipe having

a flexible connection; a pipe leading from the exhaust side of both rear cylinders; a feed water heater connected to said pipe; and an exhaust pipe connected with the feed water heater and terminating at the rear of the tender.

In testimony whereof, I have signed my

name to this specification, in the presence of two subscribing witnesses.

SAMUEL M. VAUCLAIN.
